DESIGN FOR A RUG.

Design No. 16,214, dated August 25, 1885.

UNITED STATES PATENT OFFICE.

ADOLPH PETZOLD, OF PHILADELPHIA, PENNSYLVANIA.

DESIGN FOR A RUG.

SPECIFICATION forming part of Design No. 16,214, dated August 25, 1885.

Application filed July 13, 1885. Term of patent 3½ years.

To all whom it may concern:

Be it known that I, ADOLPH PETZOLD, a citizen of the United States, and a resident of Philadelphia, Pennsylvania, have invented and produced a new and original Design for a Rug, of which the following is a specification, reference being had to the accompanying photographic illustration, to which reference is made.

10 The accompanying photographic illustration represents a full view of my rug. The design consists of an outer groundwork, A, in rectangular plaid or checkered figures, partially surrounding an interior oval panel, 15 B, which is provided with a border, C. This panel is ornamented with two birds, D D', (owls,) sitting on the leafless branch of a tree, E. A third bird, F, (also an owl,) is represented in full flight toward the same perch.

20 The background G of the panel represents a

cloudy sky, with a moon, H. One end of the oval is partially surrounded by a large cluster of flowers, I, and leaves J.

The leading features of my design are the middle panel, B, on the surrounding groundwork, with the cluster of flowers I and leaves J ornamenting one end of the rug and joining the middle panel, substantially as shown, said middle panel being ornamented with the representation of two large birds, D D', sitting on 25 the limb of a tree, E, and a third bird, F, in full flight toward the perch or limb.

What I claim as new is—

The design for a rug, substantially as shown and described.

ADOLPH PETZOLD.
